DESIGN FOR A TEXTILE FABRIC

Maclyn L. Guhl, Forest Hills, N. Y.

Application April 27, 1940, Serial No. 91,992

Term of patent 3½ years

To all whom it may concern:

Be it known that I, Maclyn L. Guhl, a citizen of the United States of America, residing in Forest Hills, in the county of Queens and State of New York, have invented a new, original, and ornamental Design for a Textile Fabric, of which the following is a specification, reference being had to the accompanying drawing, forming part thereof.

The figure is a plan view of a textile fabric, showing my new design, the unit of which is enclosed within the dot-dash lines.

I claim:

The ornamental design for a textile fabric, substantially as shown and described.

MACLYN L. GUHL.
